Primary Examiner — Robert M Spear*Assistant Examiner* — Marissa J Cash(74) *Attorney, Agent, or Firm* — George R. McGuire; Bond Schoeneck & King, PLLC(57) **CLAIM**

The ornamental design for a flying toy unicorn, as shown and described.

DESCRIPTION

FIG. 1 is a perspective view of the flying toy unicorn; FIG. 2 is a front view of the flying toy unicorn shown in FIG. 1;

FIG. 3 is a rear view of the flying toy unicorn shown in FIG. 1;

FIG. 4 is a right side view of the flying toy unicorn shown in FIG. 1;

FIG. 5 is a left side view of the flying toy unicorn shown in FIG. 1;

FIG. 6 is a top view of the flying toy unicorn shown in FIG. 1; and,

FIG. 7 is a bottom view of the flying toy unicorn shown in FIG. 1.

All surfaces of the flying toy unicorn are claimed; the broken lines represent environmental structure and form no part of the claim.
